(57) **CLAIM**

The ornamental design for a combined label and pourer for bottle, as shown and described.

DESCRIPTION

FIG. 1 is a perspective view of a combined label and pourer for bottle showing my new design;

FIG. 2 is a perspective view of a combined label and pourer for bottle shown in an environment of use;

FIG. 3 is an enlarged top view of FIG. 1;

FIG. 4 is a left view thereof;

FIG. 5 is a front elevational view thereof;

FIG. 6 is a right side view thereof;

FIG. 7 is an enlarged bottom plan view thereof;

FIG. 8 is a back elevational view thereof;

FIG. 9 is a perspective of a combined label and pourer for bottle shown in an environment of use in an alternate configuration; and,

FIG. 10 is a perspective view of a combined label and pourer for bottle shown in an environment of use in another alternate configuration.

The dotted broken lines in FIG. 3 and 7 define the bounds of the claimed design and form no part thereof.

The broken lines showing the bottle are for the purpose of illustrating environmental structure and form no part of the claimed design.
